(57) **CLAIM**

The ornamental design for a golf tee, as shown and described.

DESCRIPTION

FIG. 1 is a perspective view showing our new design for a golf tee in relation to a conventional golf ball depicted in phantom lines;

FIG. 2 is a front view of FIG. 1;

FIG. 3 is a side view of FIG. 1;

FIG. 4 is a rear view of FIG. 1;

FIG. 5 is an opposite side view of FIG. 1;

FIG. 6 is a top view of FIG. 1; and,

FIG. 7 is a bottom view of FIG. 1.

The golf ball shown in broken lines and upper surface portion wholly obscured by the golf ball form no part of the claimed design.
